UNITED STATES PATENT OFFICE

2,537,176

OCCUPANT PROPELLED ROUNABOUT

George Vlahov, Lynbrook, N. Y.

Application September 12, 1947, Serial No. 773,648

2 Claims. (Cl. 272—33)

1

This invention relates to amusement devices of the type which rotate on a vertical axis after the manner of merry-go-rounds, and is best embodied in the form of seats suspended from a rotative cross member or sweep arm that extends across the vertical axis and carries a seat in suspension from each end.

More particularly, the device is of the type which supplies the riders or occupants with means to develop a propelling force that will exert a torque on the device and so cause it to rotate. The propelling means include pedal units similar to bicycle pedals conveniently disposed with relation to each seat. Specifically, in accordance with the invention, the device is equipped with air propellers, one for each seat, all directed so as to produce torques in the same angular direction, and each operatively connected to one of the pedal units.

Preferably the seats are suspended from the cross member so that the attachment is rotatable on a horizontal axis, which will permit the seats to swing outward to an inclined plane under the influence of centrifugal force. The seats are so mounted as to be adjustable toward and away from the respective pedal units.

Simplicity and cheapness as well as strength being objects of the invention, the device is preferably made in large part of tubular members and conventional pipe fittings with a minimum of special parts. The embodiment illustrated in the drawings will now be described, following which the invention will be pointed out in claims.

Fig. 1 is a front elevation of an embodiment of the invention.

Fig. 2 is a side elevation of the same.

Fig. 3 is an enlarged sectional elevation of a portion on the line 3—3 of Fig. 1.

Fig. 4 is a detail sectional elevation on line 4—4 of Fig. 3.

Fig. 5 is an enlarged sectional detail of the top end of the column and its immediately associated parts.

Fig. 6 is an enlarged vertical section of the gear box and contents and associated parts, on the broken line 6—6 of Fig. 7.

Fig. 7 is a vertical section of the same on the line 7—7 of Fig. 6.

Fig. 8 is a sectional plan of the same on the line 8—8 of Fig. 6.

As shown, the device has a central fixed supporting post or column 1 on which the rotative parts are supported and turn. A cross member 2 is shown as a straight tube disposed horizontally across the axis of the column 1 and extending equally in opposite directions therefrom and

2

mounted so as to turn upon the axis of the column at a height from the ground sufficient to accommodate the hanging seats hereinafter described. Manifestly the two-branching arms may be inclined to the horizontal.

For the purpose of rotation, this cross member is provided at its center with a right angle stub shaft 3 which bears in a ball bearing 4 in the top of the column 1. A T-fitting 5 serves to attach the cross member 2 to its stub shaft 3, the member 2 extending through the tubular head of the fitting and being free to turn on its axis therein, and the upper enlarged end of the stub shaft being shown as extending into the tubular stem of the fitting and bolted thereto. The top of the column is closed by a cap 6. Also seated in a socket on the top of the fitting 5 is a vertical rod 7 having a ring in its upper end from which extend guy rods 8 attached to the ends of the cross member 2, as will hereinafter more particularly appear. Collars 5a are attached to the member 2 by set screws on opposite ends of the head of the fitting 5 to prevent relative longitudinal movement of the member 2.

It is thus evident that with proper balance the cross member 2 can easily be caused to turn on its bearing, under which condition the member functions as a sweep arm and is so referred to herein. To produce a torque for this purpose, the rotating member is provided with two air propellers, 9 and 10, one on each end and the two propellers facing in the same angular direction. These propellers and their mountings are duplicates, and, therefore, a description of one will be applicable to both.

Each propeller is mounted on the end of a propeller arm 11 which is suspended from the respective end of the cross member or sweep arm 2. The hanger for this suspension purpose consists of two T-fittings the stems of which are secured together by a nipple. The upper fitting 12 is disposed on the respective end of the cross member 2 and is free to turn thereon, and is constrained against relative longitudinal movement therein by a collar 13 on the cross member at the inner end of the fitting 12 and a cap 14 on the cross member at the outer end of the fitting. This cap 14 has a ring on its outer face to which the outer end of the respective guy rod 8 is attached, the cross member 2 being thus restrained from rotation upon its axis. Thus the ends of the cross member which carry the weight of the occupants, are braced.

The lower fitting 15 which receives the arm 11 is attached to the fitting 12 by a nipple 16 with its tubular head horizontal and at right

angles to that of the fitting 12. The arm 11 fits into this fitting 15 at substantially midway of the ends of the arm and is free to turn in the fitting as a bearing. Collars 15a which are secured on the arm 11 by set screws at opposite ends of the tubular head of the fitting 15, restrain the arm 11 from relative longitudinal movement.

The propeller is mounted on the front end of the arm 11 for rotation upon the axis of the arm. For this purpose, in the construction shown, the front end of the arm 11 is screwed into an internally screw threaded end of the tubular head of a T-fitting 17, and in the opposite end of this head is disposed a ball bearing 18 in which bears a stub shaft 19 on the outer end of which the hub 20 of the propeller is secured against relative rotation. A cap nut 21 screws on the outer end of the stub shaft 19 and bears against the hub 20 and draws the hub of a bevel gear 22, which is secured on the inner end of the stub shaft, against the bearing 19 and thus secures the propeller assembly in its bearing.

Vertically depending from the fitting 17 is a tubular bearing member 23 of a length to extend within a short distance from the ground. For attachment, the upper end of the bearing member is screw threaded and screws into the internally screw threaded stem of the fitting 17. Disposed at intervals within this tubular bearing member are ball bearings 24 in which bears a drive shaft 25 having on its upper end a bevel gear 26 in mesh with bevel gear 22, and having on its lower end a bevel gear 27. These bevel gears on the shaft 25 bear with their hubs against the end bearings 24 and thus position and restrain the shaft longitudinally.

Secured on the lower end of each tubular bearing member 23 is a gear box 28, the parts being proportioned so that the gear boxes clear the ground. As shown, the gear box is screwed on to the lower end of the bearing member, a supplemental collar 29 with an internally screw threaded neck and secured on the top of the box in register with an opening in the box, being provided for the purpose.

The box is relatively narrow in its transverse dimension and one of its side plates 30 is removable. A transverse pedal shaft 31 bears in the box in bearings 32 one of which is on the inner face of the removable side 30 and the other of which is on the inner face of the opposing side. Hubs 33 are on the outer faces of these two sides, and pedals 34 on the ends of the shaft 31 bear against the hubs 33 and hold the shaft against longitudinal movement.

A gear 35 on the pedal shaft 31 meshes with a pinion 36 on a countershaft 37 which also bears in ball bearings 38 on the inner faces of the sides of the box 28. Fixed on this shaft 37 is a bevel gear 39 which meshes with the bevel gear 27 on the lower end of drive shaft 25.

It is thus apparent that rotation of the pedals 34 will drive shaft 25 through gears 35, 36, 39 and 27 at an increase in speed ratio, and that rotation of shaft 25 will produce rotation of the respective propeller through gears 26 and 22. The rotation of the propeller by reaction against the air will produce a pull in the direction of the arm 11 a component of which exerts a torque on the cross member 2 about the axis of its shaft 3. Sufficiently rapid rotation will cause the members 23 and parts supported thereby to swing out from centrifugal force about the axis

of the tubular bearings 15, as indicated by broken lines in Fig. 1.

A seat is provided for the comfort and convenience of the operators, in proximity to each pedal unit, and preferably the seat is made adjustable to accommodate operators of different size.

As shown, the seats are attached to and supported by the gear boxes. Bosses on the rear face of the gear box provide attachment sockets for two seat frame rods 40 which are disposed in the same vertical plane and rise vertically from the box and then are bent to provide a horizontal section. A seat 41 is disposed on the horizontal section and is provided with a spring back rest 42. The seat is adjustably secured on the rods 40 by means of an adjustable socket member 47 which has horizontal holes for fitting over the rods 40, and vertical holes for receiving a pair of seat pins 43 that straddle the rods 40. The height of the seat is adjusted by regulating the extent to which the seat pins 43 are permitted to enter their sockets in the member 47.

The resiliency of the rods 40 makes it desirable to support their outer ends. For this purpose, in the construction shown, the two outer ends of the rods 40 are joined by a vertical coupling member 44, and the upper end of this is supported from the outer end of the arm 11 by a rod or chain 45 that loops with its lower end into a ring on the member 44 and with its upper end into a ring on a cap 46 on the end of the arm 11.

It is manifest that the propelling mechanisms may be other than two in number, that the frame may be otherwise designed and assembled, and that many modifications may be made in the construction shown in the drawings and above particularly described within the principle and scope of the invention as defined in the following claims.

What is claimed is:

1. An amusement device comprising a supporting column, a sweep member carried by and mounted at its center for rotation on the column, a transverse bearing directly mounted on each end of the sweep member and having freedom of movement about the axis of the member, a propeller arm rotatably mounted in each bearing and extending therefrom substantially at each end, a propeller carried by and rotatable upon one end of each propeller arm, drive means on each propeller arm for the respective propeller, suspension means rigidly attached to and supported by each propeller arm adjacent the drive means, pedal operated means supported by the suspension means and operatively connected to the drive means, a seat, and means supportably attaching the seat to the suspension means and to the other end of the propeller arm.

2. An amusement device comprising a supporting column, a sweep member carried by and mounted at its center for rotation on the column, a transverse bearing directly mounted on each end of the sweep member and having freedom of movement about the axis of the member, a propeller arm rotatably mounted in each bearing and extending therefrom substantially at each end, a propeller carried by and rotatable upon one end of each propeller arm, a drive gear for each propeller carried by the propeller arm, a hollow tube rigidly attached to and depending from the propeller arm adjacent the drive gear, a gear box attached to the lower end of the tube, a pedal operated gearing in the gear box, a shaft

In the tube operatively connecting the drive gear and the gearing in the gear box, a seat, and means supportably attaching the seat to the gear box and to the other end of the propeller arm.
